MATERIAL HANDLING APPARATUS

Harry F. Vickers, Los Angeles, Calif.

Application May 21, 1930, Serial No. 454,316

9 Claims. (Cl. 198—219)

This invention relates, generally, to material handling apparatus and has particular reference to apparatus suitable for embodiment in or application to a heat treating furnace, or the like. It is a general object of this invention to provide an apparatus for handling material in a furnace, or the like, so that it is advanced through the furnace automatically at a predetermined rate.

10 The apparatus or device provided by this invention is useful, generally, for handling material or objects and is particularly useful and practical in handling material in a furnace, or the like. For the purpose of making a disclosure of 15 a typical application of the invention I will set forth a form of the invention designed particularly for a heat treating furnace and designed to handle bars or lengths of shafting, or the like. It is to be understood, of course, that the broader 20 principles of the invention are not to be construed as limited to the details hereinafter set forth.

It is a general object of this invention to provide a material handling apparatus for a furnace, 25 or the like, in which the principal elements are operated hydraulically.

Another object of this invention is to provide apparatus of the character mentioned in which there is a material advancing or moving element 30 such as a rack operable vertically and horizontally, the vertical movement being effected through one fluid pressure actuated mechanism and the horizontal movement being effected through another fluid pressure actuated mechanism.

35 It is a further object of this invention to provide apparatus of the character just mentioned in which the two fluid pressure actuated mechanisms are related or interconnected to cooperate so that they function successively, one being put into operation at the completion of an operation of the other.

It is a further object of the invention to provide apparatus of the character mentioned in which 45 the fluid pressure actuated mechanisms are connected in combination with means for supplying an actuating fluid, the said mechanisms and the said means constituting a unit which operates through one complete cycle to cause a definite 50 advance of material in the furnace upon being set in operation.

It is another object of this invention to provide a control for apparatus of the character mentioned operable to put the parts above mentioned 55 into operation at definite timed intervals or in

definite timed relation to other machines or apparatus.

The various objects and features of my invention will be best and more fully understood from the following detailed description of a typical 60 form and application of the invention, throughout which description reference is had to the accompanying drawings, in which:

Fig. 1 is a longitudinal detailed sectional view of a typical type of heat treating furnace embodying the apparatus provided by this invention, the section being taken to facilitate illustration of the parts provided by the invention. Fig. 2 is a detailed transverse sectional view taken as indicated by line 2—2 on Fig. 1. Figs. 3, 4, 5, and 6 70 are enlarged detailed views illustrating the material handling parts of the apparatus, being views showing the manner in which objects such as rods are handled so that they are turned or rotated as they are advanced through the furnace, 75 and Fig. 7 is a diagrammatic view illustrating the various elements of the invention and showing the manner in which they are interconnected.

The furnace illustrated in the drawings is of more or less common form and construction in 80 that it is a horizontal furnace including a bottom or base 10, sides 11, a top 12, a front end 13, and a rear end 14. The various parts just mentioned form a horizontal chamber 15 for carrying heating elements, burners, or other heat generating 85 means (not shown). The front end 13 of the furnace is provided with a suitably shielded opening 16 through which material or objects to be heat treated are introduced into the chamber 15, while the rear end 14 is provided with a chute 90 17 through which the objects after being heated are discharged from the furnace into a quenching tank 18, or the like. The particular furnace illustrated is designed to handle bars or lengths of shafting, or the like, and therefore the discharge 95 chute 17 is provided with an offset or bend 19 which operates to control the drop or discharge of objects so that they enter the tank 18 sideways and not one end before the other.

The apparatus or mechanism provided by the 100 present invention includes, generally, a stationary rack 20 for holding or supporting the objects when they are not in motion, a movable rack 21 for advancing or moving the objects, means 22 supporting the movable rack 21 for vertical movement, means 23 for operating the movable rack 21 vertically through the means 22, means 24 for operating the movable rack 21 horizontally, means 25 for supplying actuating fluid to the means 23 and 24, means 26 interconnecting the means 23 110

and 24 so that their operations are synchronized, and control means 27 for timing the operation of the apparatus or for relating its action to that of another machine or apparatus.

- 5 The stationary rack 20 extends longitudinally through the furnace and preferably projects from the front of the furnace through the opening 16 so that it has a portion at the exterior of the furnace onto which objects can be arranged conveniently. The stationary rack preferably includes a plurality of spaced longitudinal elements or rails 28 mounted on the furnace floor 29 to project upwardly a suitable distance therefrom. In the case illustrated the furnace floor is mounted on suitable beams 30 extending longitudinally in the furnace. The apparatus illustrated being designed particularly to handle bars, or like objects, the upper edges or faces of the rails are provided with suitably rounded notches 31. The 10 several rails of the stationary rack 20 are parallel to each other and are spaced so that the objects are supported at suitable intervals. The notches 31 in the rails 28 are uniform in size and shape and the notches of the several rails are in line 15 transversely of the furnace.

The movable rack 21 is arranged in the furnace to cooperate with the stationary rack to advance objects along the stationary rack or through the furnace. The movable rack 21 comprises primarily one or more rails 32 similar to the rails 28 but adapted to move vertically to lift the objects from the stationary rails and lower them onto the stationary rails 20 and to move horizontally to shift the positions of the objects longitudinally of the stationary rails 20. In the particular construction illustrated the number and arrangement of rails 32 corresponds with that of the stationary rails 28, there being a movable rail adjacent and parallel to each stationary rail. In the 20 particular construction shown the rails 32 are mounted on movable beams 34 through movable floor sections 35 operable in longitudinal openings or slots 36 provided in the furnace floor 29. In the particular case illustrated two beams 34 support each movable floor section 35 and there are two rails 32 on each floor section 35. The upper edges or faces of the rails 32 are provided with notches 37 similar in shape and arrangement to the notches 31 in the rails 28. In the preferred setting of the apparatus the rails 32 are longitudinally related to the rails 28 so that the notches of the rails are initially related as illustrated in Fig. 3. Upon straight upward or vertical movement of the rails 32 from the position shown in Fig. 3 to that shown in Fig. 4, the objects are lifted from the rails 28 by the rails 32 and are rotated in the direction indicated by the arrow in Fig. 4 as they center themselves in the notches 37 of the rails 32. After the movable rails have 30 advanced horizontally to a position such as is shown in Fig. 5, the movable rails are lowered vertically allowing the objects to be returned to the stationary rails, the notches 31 and 37 being related during the lowering operation so that the objects are again rotated in the direction indicated by the arrow in Fig. 4 as they center themselves in the notches 31. The letter X is applied to a single object in Figs. 3, 4, 5, and 6 so that the travel and motion of this object can be readily traced in the drawings.

The means 22 supporting the movable rack 21 is adapted to be operated to move the rack vertically. In the preferred construction the means 22 includes a plurality of shafts 38 mounted transversely below the beams 34 at points spaced lon-

gitudinally of the furnace, arms 39 projecting from the shafts 38 to engage under the beams 34, arms 40 projecting downwardly from the shafts, and a connecting rod 41 operatively connecting the arms 40 of the several shafts. The 80 arms 39 and 40 are keyed or otherwise fixed on the shafts 38 so that movement of the arms 40, as by operation of the connecting rod 41, causes turning of the shafts and consequent swinging of the arms 39 so that the beams 34, resting on the arms 39, move vertically. In the preferred construction rollers 42 are provided on the outer ends of the arms 39 to reduce friction between the engagement of the arms and the beams 34.

The means 23 provided for operating the movable rack 21 through the supporting means 22 is a fluid pressure actuated means including, generally, a cylinder 43, a piston 44 operable in the cylinder, and a control valve 45 for the cylinder and piston mechanism. The cylinder 43 is mounted at a suitable point, preferably at the forward end of the furnace and a rod 46 carrying the piston 44 is suitably connected or linked to the connecting rod 41 so that movement of the piston in the cylinder causes longitudinal movement of the rod 41. The valve 45 includes, generally, a cylindrical body 47, and a piston valve 48 operable in the body 47. A fluid supply conduit 49 connects with the middle portion of the cylinder 47 while conduits 50 and 51 connect the 105 end portions of the cylinder 47 with the ends of the cylinder 43 as will be apparent from the diagram Fig. 7. An exhaust or discharge line 52 is suitably connected with the cylinder so that when the supply line 49 is put in communication with either end of the cylinder 47 the other end of the cylinder is in communication with the exhaust line 52.

The means 24 provided for operating or moving the movable rack 21 horizontally includes, 115 generally, a cylinder 53, a piston 54 operable in the cylinder, and a control valve 55. The cylinder 53 is preferably mounted at the forward end of the furnace and the rod 56 carrying the piston 54 is suitably connected or linked directly to the 120 movable rack 21, say, for instance, to the beams of the rack. With this arrangement movement of the piston 54 in the cylinder 53 causes corresponding movement of the movable rack 21, the rack 21 being free to move horizontally due to 125 its being supported on rollers as hereinabove described.

The valve 55 includes a cylindrical body 57 carrying a piston valve 58. The fluid supply line 49 connects with the middle portion of the cylinder 57 while lines 60 and 61 connect the ends of the cylinder 57 with the ends of the cylinder 53. An exhaust or return line 62 connects with the cylinder 57 in the same manner that the exhaust line 52 connects with the cylinder 45.

The means 25 for supplying actuating fluid to the means 23 and 24 is preferably a motor pump unit including, generally, an electric motor 66 and a suitable fluid handling pump 67. This unit may be such as to deliver fluid at a certain volume and pressure when in operation. In the arrangement illustrated the pump is adapted to draw fluid from a reservoir 68 and deliver it to the fluid supply line 49. The exhaust lines 52 and 62 connect with the reservoir 68 so that the fluid after circulating through the system is returned to the reservoir.

The means 26 interconnecting the means 23 and 24 connects the means 23 and 24 so that their actions or operations are synchronized giving 150

them a definite cycle of operation. In accordance with the invention the connecting means 26 is such that upon operation of the means 25 the means 23 first operates to move the movable rack 21 up vertically so that objects are lifted from the stationary rack 20 whereupon the means 24 operates to advance the movable rack horizontally to advance the objects through the furnace whereupon the means 23 functions to allow the movable rack to lower and move down vertically returning the objects to the stationary rack in the advanced position whereupon the means 24 operates to return or retract the movable rack to the original or starting position ready for another operation. In the form of the invention shown the means 26 includes, generally, an arm 69 having one end connected to the stem 70 of valve 58 and the other end related to spaced stops 71 on the rod 46 carrying the piston 44, and an arm 72 connected to the stem 73 of the valve 48 and related to stops 75 on the piston rod 56 carrying the piston 54. When the operation of the apparatus starts the valve 48 is in position so that fluid is admitted from the supply line 49 to the cylinder 43 to move the piston in a direction to cause the movable rack 21 to lift or move vertically. As this operation is completed one of the stops 71 on the piston rod 46 operates the arm 69 so that the valve 58 is moved in the cylinder 57 so that fluid is admitted from the supply line 49 to the cylinder 53 to cause the piston 54 to move so that the movable rack advances in the furnace. As this operation is completed the arm 72 is operated by a stop 75 on the rod 56 so that the valve 48 is operated to allow fluid from the supply line 49 to enter the cylinder 43 so that the piston 44 is moved to lower the rack. At the completion of this operation one of the stops 71 operates the arm 69 so that the valve 58 admits fluid from the fluid supply line 49 to the cylinder 53 causing the piston 54 to be operated to return the rack to the normal or original position at the close of which operation the valve 48 is operated through the arm 72 to leave the mechanism set so that it is ready for another cycle of operation.

It is to be understood, of course, that various auxiliaries or controls may be provided in the system just described; for instance, suitable check and stop valves may be arranged where necessary or desirable. Further, it will be apparent that the pump 67 employed in the means 25 may be a pump operating to deliver fluid at the desired rate and at the desired pressure to cause operation of the mechanism through the cycle above described in the desired length of time.

The control means 27 is provided to automatically control the mechanism above described either from a suitable timer or in suitable timed relation to other apparatus. For example, in practice it may be desired to have the present apparatus operate in synchronism with a drawing furnace, or the like. The control means 27 includes, generally, a magnetic starting switch 80 controlling the motor 66 of means 25 and a timer switch and disconnect switch connected in parallel with the actuating circuit of the switch 80. The magnetic starting switch 80 may be any suitable type of switch operable to close the motor circuit upon the switch circuit being closed and to leave the motor circuit closed until such time as the switch control circuit is opened. The timer switch and disconnect switch are connected in parallel in the switch control circuit to control the action of the switch 80. The timer switch illustrated in the drawings is adapted to be driven

from any suitable mechanism such as a clock or other machine and includes, generally, a cam 85 to be operated by the clock or other machine, a movable contact 86, a stationary contact 87, and a follower 88 on the movable contact cooperating with the cam. The profile of the cam is such that for each revolution of the cam there is a period during which the contact 86 is in engagement with the contact 87 thus closing the circuit through the timer. The disconnect switch is connected in the control circuit of the switch 80 in with the timer switch and includes, generally, a movable contact 90, a stationary contact 91, and an operating member 92. The contacts 90 and 91 are normally together to close the circuit through the switch. The actuating member 92 is carried by a movable part of the mechanism; for instance, by one of the beams 34 of the movable rack 21 and is related to the movable contact 90 so that the movable contact is moved away from the contact 91 as the movable rack is returned to or reaches its original or starting position.

From the foregoing description it will be apparent that when the apparatus is in its normal position ready for operation the disconnect switch of the control is open, contact 90 being held away from the contact 91 by the actuating member 92. The valve 48 is positioned in the cylinder 45 so that fluid will be admitted to the cylinder 43 to cause lifting of the movable rack 21 as soon as circulation of fluid is started in the system. The parts will all remain at rest until the timer cam 85 operates to a position allowing the contact 86 to engage the contact 87 at which time the control circuit for the switch 80 is closed causing actuation of the switch 80 so that the motor 66 is put in operation. As soon as the motor 66 starts operation the pump 67 operates to circulate fluid through the system causing the parts to go through the cycle of operation above described until the movable rack is returned to its original position at which time the actuating member 92 of the disconnect switch opens the circuit to the control switch 80 by moving the contact 90 away from the contact 91, the timer switch having during operation of the apparatus operated so that it is open by the time the movable rack reaches the end of its cycle. It will thus be apparent that in the control means 27 the timer switch operates as a starting switch for closing the circuit to the switch 80, while the disconnect switch operates to open the control circuit at the completion of the cycle of operation of the mechanism. The feature of this system or arrangement is that the operation of the mechanism is started at a definite time or in definite relation to other means, such as a clock or other machine, whereas the operation of the machine is stopped only upon full completion of the cycle of operation of the machine.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A material handling device including, a movable rack, fluid pressure actuated means for operating the rack vertically, fluid pressure actuated means for operating the rack horizontally, a source of actuating fluid pressure for supplying fluid under pressure to said means, and an electrical control means for controlling the delivery of the actuating fluid pressure to said means oper- 145

able to provide for definite time intervals between successive cycles of operation of said means, the last named means including an actuating part on the rack, and a switch adapted to be operatively engaged by said part.

- 5 2. A material handling device including, a movable rack, fluid pressure actuated means for operating the rack vertically, fluid pressure actuating means for operating the rack horizontally, pressure generating means for supplying fluid under pressure to both of said fluid pressure actuated means, power means for operating the pressure generating means, and an electric control operable by the rack for governing the actuation of 10 the power generating means.

- 15 3. A material handling device including, a movable rack, fluid pressure actuated means for operating the rack vertically, fluid pressure actuated means for operating the rack horizontally, pressure generating means for supplying fluid under pressure to both of said fluid pressure actuated means, a control for the pressure generating means including a timer switch to start operation 20 of the pressure generating means and a disconnect switch operable by one of said fluid pressure actuated means through the movement of the rack to stop operation of the pressure generating means.

- 25 4. A material handling device including, a movable rack, fluid pressure actuated means for operating the rack vertically, fluid pressure actuated means for operating the rack horizontally, pressure generating means for supplying fluid under pressure to both of said fluid pressure actuated means, a control for governing the actuation of 30 the pressure generating means including a timer switch to start operation of the pressure generating means and a disconnect switch to stop operation of the pressure generating means, the disconnect switch being operable by the rack.

- 35 5. A device for handling cylindrical or rollable objects including a stationary rack, a movable rack, the racks being adapted to carry the objects, and means for moving the movable rack vertically 40 between positions above and below that of the stationary rack and for moving the rack horizontally in said positions to cause the objects to be alternately carried by the racks and to be advanced horizontally, the upper edges of the 45 racks having rounded object carrying notches in which the objects turn or roll when engaged by the racks.

- 50 6. A device for handling cylindrical or rollable objects including a stationary rack, a movable rack, the racks being adapted to carry the objects and means for moving the movable rack vertically 55 between positions above and below that of the

stationary rack and for moving the rack horizontally in said positions to cause the objects to be alternately carried by the racks and to be advanced horizontally, the upper edges of the racks having rounded object carrying notches, the notches in the two racks being in different horizontal positions whereby the objects roll to the bottoms of the notches when received in the notches.

80 7. A material handling device including a movable rack, fluid pressure actuated means for operating the rack vertically, fluid pressure actuated means for operating the rack horizontally, an interconnection between said means whereby they operate successively through a definite cycle of 85 operation, pressure generating means for supplying fluid under pressure to both of said fluid pressure actuated means, and a control governing operation of the pressure generating means including a timer switch to start operation of the pressure generating means, and a disconnect switch to stop operation of the pressure generating means, the disconnect switch being operable by the rack.

90 8. A material handling device including a movable rack, fluid pressure actuated means for operating the rack vertically, fluid pressure actuated means for operating the rack horizontally, an interconnection between said means whereby they operate successively through a definite cycle of 95 operation, pressure generating means for supplying fluid under pressure to both of said fluid pressure actuated means, power means for operating the pressure generating means, a starting switch for the power means, a control circuit for controlling the starting switch, a timer switch operable to close said circuit, and a disconnect switch operable by the rack to open said circuit and thereby stop the power means.

100 9. A conveyor including, a rack, a fluid pressure actuated mechanism for moving the rack vertically, a fluid pressure actuated mechanism for moving the rack horizontally a source of actuating fluid pressure for operating the mechanisms, and a control including, electrical means for initiating the delivery of actuating fluid pressure from said source to the mechanisms, means for suspending the delivery of actuating fluid pressure from said source to the mechanisms, the last named means including an actuating part 105 movable with the rack, and a switch governing the delivery of actuating fluid pressure and operated by said actuating part, and an interconnection between said mechanisms whereby they operate successively through a definite cycle of 110 operation.
